CARGO CARRIER FOR A PNEUMATIC TUBE

George R. Cook and Gerrard Pero, Rochester, N.Y., assignors to Cutler Mail Chute Company, Rochester, N.Y., a corporation of New York

Filed Dec. 6, 1968, Ser. No. 14,823

Term of patent 14 years

Int. Cl. D9—07

U.S. Cl. D9—171

FIG. 1.

FIG. 2.

FIG. 3.

FIG. 4.

FIG. 1 is a front elevational view of a cargo carrier for a pneumatic tube showing our new design;

FIG. 2 is a top plan view;

FIG. 3 is an elevational view looking from the left of FIG. 1; and

FIG. 4 is an elevational view looking from the right of FIG. 1 thereof.

We claim:

The ornamental design for a cargo carrier for a pneumatic tube, as shown.
